UNITED STATES PATENT OFFICE.

ANTHIME BERNIER, OF NEW YORK, N. Y.

RAILWAY-TIE.

1,082,674.

Specification of Letters Patent.

Patented Dec. 30, 1913.

Application filed October 11, 1913. Serial No. 794,625.

To all whom it may concern:

Be it known that I, ANTHIME BERNIER, a citizen of the United States, and residing at New York, in the county of New York and 5 State of New York, have invented certain new and useful Improvements in Railway-Ties, of which the following is a specification, such as will enable those skilled in the art to which it appertains to make and use 10 the same.

This invention relates to railway ties, and the object thereof is to provide an improved composition device of this class employing both wood and metal; a further object being 15 to provide a railway tie which will possess all the necessary strength, and at the same time be economical in construction and use; and with these and other objects in view, the invention consists in a railway tie constructed as hereinafter described and claimed.

The invention is fully disclosed in the following specification of which the accompanying drawing forms a part, in which the separate parts of my improvement are designated by suitable reference characters in 25 each of the views, and in which—

Figure 1 is a plan view showing two of my improved railway ties and rails mounted thereon; Fig. 2 a section on the line 2—2 of 30 Fig. 1, and, Fig. 3 a section on the line 3—3 of Fig. 1.

My improved railway tie is made entirely of metal except parts thereof on which the rails are placed, and said tie comprises a 35 central longitudinal vertical web portion a having base flanges a^2 and a horizontal top plate a^3 forming top side flanges a^4 similar to the base flanges a^2 between the end portions of the rail. The end portions of the 40 rail at the top thereof are provided with oblong heads b having deep and wide longitudinal recesses b^2 in which are placed blocks c of wood or other suitable fibrous material, and the sides of the blocks c which may be 45 slipped into the recesses b^2 are inclined upwardly and inwardly, as shown at c^2 , and the inner walls of the sides of the heads b are similarly formed, and this aids in holding the blocks c in the heads b of the ties. The 50 blocks c are also secured in the recesses b^2 by bolt d which are passed upwardly through the bottoms of the heads b and through said blocks and provided with nuts d^2 , or said bolts may be passed downwardly through

the blocks c and the bottoms of the heads b , 55 if desired.

The tops of the side walls of the heads b are cut out transversely, as shown at e to form recesses to receive the base flanges f^2 of the rails f , and with this construction the 60 blocks c extend above the heads b or the sides thereof and form fibrous cushions for the rails f , and said rails are secured to said blocks by spikes g which are driven downwardly into said blocks in the usual manner, and the heads of which overlap the base flanges of the rail. The webs of the ties are also preferably strengthened beneath 65 the heads b by webs or ribs h , and the central web portion of the ties may be similarly 70 braced if desired.

The main part of the tie, or the metal parts thereof, may be formed in any desired manner, and may consist of separate parts secured together if desired, and in this way 75 I provide a railway tie possessing the greatest possible strength and also involving wood or fibrous portions which support the rails and to which the rails are secured, and by means of the particular form of the tie 80 in cross section, the greatest possible strength is produced in proportion to the amount or weight of the material employed.

Having fully described my invention what I claim as new and desire to secure by Letters Patent is:—

A railway tie comprising a central longitudinal web portion having base flanges, and a top plate forming corresponding top flanges, the ends of the tie being provided at 90 the top thereof with longitudinal heads in which are formed longitudinal recesses which open outwardly through the ends of the tie, and in which are secured blocks of wood on which the rails are placed, the sides 95 of said heads being lower than said blocks of wood, when the latter are secured in position.

In testimony that I claim the foregoing as my invention I have signed my name in 100 presence of the subscribing witnesses this 4th day of October, 1913.

ANTHIME ^{bis} X BERNIER.
